(57) **CLAIM**

The ornamental design for the power input terminal for computers, as shown and described.

DESCRIPTION

FIG. 1 is a front perspective view;

FIG. 2 is a front view;

FIG. 3 is a rear view;

FIG. 4 is a left side view;

FIG. 5 is a right side view;

FIG. 6 is a top plan view; and,

FIG. 7 is a bottom plan view.

The surface shading on the illustrated power input terminal for computers is intended only to show the character and contour of the surfaces and not surface indicia.
